UNITED STATES PATENT OFFICE.

JOHN SCHADE, JR., OF NEW YORK, N. Y., ASSIGNOR TO FAHNESTOCK ELECTRIC COMPANY, A CORPORATION OF WEST VIRGINIA.

DESIGN FOR SPRING FASTENING DEVICE FOR ELECTRICAL CONDUCTORS.

41,493.

Specification for Design.

Patented June 20, 1911.

Application filed November 24, 1908. Serial No. 464,341. Term of patent 7 years.

To all whom it may concern:

Be it known that I, JOHN SCHADE, Jr., a citizen of the United States, and residing at the borough of Brooklyn, in the county of Kings, city and State of New York, have invented a new, original, and ornamental Design for Spring Fastening Devices for Electrical Conductors, of which the following is a specification, reference being had to the accompanying drawing, forming part thereof.

The figure is a perspective view of a spring fastening device, showing my new design.

I claim:

The ornamental design for a spring fastening device for electrical conductors, as shown.

JOHN SCHADE, JR.
